UNITED STATES PATENT OFFICE.

CHARLES B. CAMPBELL, OF WATERLOO, IOWA, ASSIGNOR TO THE STORM RAILWAY SIGNAL COMPANY, OF WATERLOO, IOWA.

MAKE-AND-BREAK SWITCH FOR ELECTRIC SIGNALS.

SPECIFICATION forming part of Letters Patent No. 739,056, dated September 15, 1903.

Application filed January 20, 1903. Serial No. 139,751. (No model.)

To all whom it may concern:

Be it known that I, CHARLES B. CAMPBELL, a citizen of the United States of America, and a resident of Waterloo, Blackhawk county, 5 Iowa, have invented certain new and useful Improvements in Make-and-Break Switches for Electric Signals, of which the following is a specification.

My invention relates to improvements in 10 automatic signals for electric railways; and the object of my improvement is to provide a make-and-break switch to be operated by contact of a trolley-wheel from below and provided with such means for breaking an 15 electrical circuit therethrough as will effectively prevent accidental reestablishing of the circuit. It is also an improvement upon the mechanism of the make-and-break switch shown and described in Patent No. 674,523, is 20 sued to Charles H. Storm May 21, 1901. The mechanism of the make-and-break switch shown, described, and separately claimed in this application is also shown and described in my application for a patent on an automatic 25 signal for electric railways executed concurrently herewith.

The above-mentioned objects I attain by the means illustrated in the accompanying drawings, in which—

30 Figure 1 is a side elevation of my improved make-and-break switch. Fig. 2 is a plan view of the same, and Fig. 3 is a detail view giving an end elevation of the swinging contact-block and pendant of said switch.

35 Similar characters of reference represent similar parts throughout the several views.

My make-and-break switch above referred to is borne upon a base-plate *a*, which is suspended above the trolley-wire. The base-plate *a* is provided with bearings *r*, within 40 which the swinging contact-block *o* is pivoted on studs *p*. A pendant *q* extends downwardly from the swing-block *o* and is slotted, that it may hang astride of the trolley-wire. The 45 upper surface of the swing-block *o* is flattened, and said block has two forked extensions containing antifriction-rollers *m* and *n*, respectively. A vertically-movable weight *g*, sustained by the guides *d* and *e*, which are 50 slidable vertically within bearings in the

frame *b c*, rests normally upon the upper flattened surface of the swing-block *o*. A cross-piece *f* connects the upper ends of the guides *d* and *e*. Spring-terminals *s* and *t* are clasped, respectively, to the insulating-blocks *u* and *v* by means of the bolted plates *w* and *y*. The free ends of these terminals are upwardly curved. A conductor 55 60 leads from the plate *w* to the setting mechanism of the signal. A conductor 38 leads from the plate *y* to the releasing mechanism of the signal. When a car passes under said switch going toward a track-section, its trolley-wheel contacts with and swings upward to a nearly horizontal position, the slotted pendant *q* carrying over the swing-block *o*, so that the roller *k*, which extends outwardly from its attached arm *h*, will move over and contact with the upper surface of the spring-terminal *s*. A current is thus established from 65 the trolley-wire through the switch to the terminal *s*, plate *w*, and conductor 37 to the setting mechanism of the signal. As the car proceeds over and passes from the track-section it passes under a second make-and-break 70 switch of the same construction, but reversed in position. The contact of the trolley-wheel with the pendant *q* of the second switch then swings the block *o* into a position where the outwardly-extending roller *l* of its attached 75 arm *i* will pass over and contact with the upper surface of the spring-terminal *t*. A current is thus established from the trolley-wire through the switch, the terminal *t*, the plate *y*, and the conductor 38 to the releasing mechanism of the signal. The action of the switch 80 when contact is effected between the roller *k* and the spring-terminal *s* is shown by the dotted lines in Fig. 1. When the trolley-wheel has passed under the pendant *q*, the superincumbent weight *g* forces the block *o* to pass into its normal position, at which time the contact is broken between the roller *k* and the terminal *s* or between the roller *l* and the terminal *t*, and in this position of the 85 parts no accidental second contact can be effected as a result of the swinging back of the block. The making and breaking of the circuit is thus rendered invariable and certain. The gravity of the movable block *g* is suffi- 90 95 100

cient to prevent displacements of the block *o* from position, except under the impelling stress of the moving trolley-wheel.

This improved make-and-break switch is 5 suitable for incorporation into any system of trolley-wheel-actuated automatic signals for electric railways wherein the setting and releasing mechanism is operated by means of solenoids or electromagnets.

10 Having described my invention, what I claim as new, and desire to secure by Letters Patent, is—

15 1. A make-and-break switch for trolley-actuated signals, consisting of a frame, a swinging contact-block pivoted in said frame and having its lower portion slotted so as to ride astride the trolley-wire, contact-arms attached to said block, a movable weight attached to guides slidable in said frame, adapted to rest 20 on said swing-block and keep its arms normally out of contact with the terminals, insulated terminals adapted to be contacted by said arms respectively when said swing-block is moved by a trolley-wheel in either direction, and conductors leading from said terminals to the signal, substantially as shown and described.

25 2. A make-and-break switch for trolley-actuated signals, consisting of a frame, a swinging contact-block pivoted in said frame having antifriction-rollers in its upper portion and having its lower portion slotted so as to ride astride the trolley-wire, contact-arms attached to said block, a movable weight attached to guides slidable in said frame, adapt-

ed to rest on said swing-block and keep its arms normally out of contact with the terminals, terminals insulated from said frame and adapted to be contacted by said arms respectively when said swing-block is moved by a trolley-wheel in either direction, and suitable conductors leading from the said terminals to the signal, substantially as shown and described.

3. A make-and-break switch for trolley-actuated signals, consisting of a frame provided with openings and having bracket-bearings, a swinging contact-block pivoted in said bracket-bearings and having antifriction-rollers pivoted in its upper part and having 50 its lower part formed into a slotted pendant adapted to ride astride of the trolley-wire, arms bearing antifriction-rollers attached to said swing-block, a vertically-movable weight attached to guides slidable in said frame and 55 adapted to rest on said swing-block and keep its roller-bearing arms normally out of contact with the terminals, insulated terminals adapted to be contacted by the rollers on said contact-arms respectively when said swing-block is moved by a trolley-wheel in either direction, and conductors leading from said terminals, substantially as shown and described.

Signed at Waterloo, Iowa, this 14th day of 65 January, 1903.

CHARLES B. CAMPBELL.
